UNITED STATES PATENT OFFICE.

CHARLES C. HANSEN, OF EASTON, PENNSYLVANIA, ASSIGNOR TO INGERSOLL-RAND COMPANY, OF JERSEY CITY, NEW JERSEY, A CORPORATION OF NEW JERSEY.

GUIDE HEAD FOR DRILL STEELS.

Application filed September 26, 1928. Serial No. 308,507.

This invention relates to rock drills, but more particularly to a guide for the working implement such as drill steels actuated by rock drills of the hammer type.

5 One object of the invention is to guide and support the overhanging portion of the working implement and another object is to insure the retention of the guide in both the operative and inoperative positions. This, in the present instance, is accomplished by the same means ordinarily used for clamping the guide arms in the operative position.

10 Other objects will be in part obvious and in part pointed out hereinafter.

In the drawings illustrating the invention and in which similar reference characters refer to similar parts,

15 Figure 1 is a side elevation of a front end 20 of a rock drill shell having the invention applied thereto,

Figure 2 is a transverse view taken through Figure 1 on the line 2—2 looking in the direction indicated by the arrows, and

25 Figure 3 is a plan view of the guide showing a modification of the invention.

30 Referring more particularly to the drawings, A represents the front end of a rock drill shell and B the front head of a rock drill for which the shell A forms a guide. The shell A is provided with lugs C to support side bolts D which in turn pivotally support at their front ends arms E comprising a guide for a working implement F 35 which projects into the front head B to receive the blows of a hammer piston (not shown).

40 The arms E may be in most respects similar to those commonly employed for guiding drill steels and accordingly have recesses G in adjacent surfaces which in the closed position of the arms E register and form a guideway for guiding the drill steel F.

45 The arms E are provided at their outer ends with the usual grooves H formed in the sides of the arms and extend over the tops thereof to receive a U-clamp J whereby the arms E are held in the operative position for guiding the drill steel F.

50 When changing drill steels in the drill, the U-clamp J is removed from the grooves H and the side arms are then rocked rearwardly of the shell A to a position similar to that illustrated in dot and dash lines in

Figure 2. In certain positions of the drill- 55 ing apparatus it is difficult to maintain the side arms in this inoperative position during the changing of the drill steel and considerable trouble and delay has been caused by the tendency of the side arms to swing forwardly to the operative or guiding position. In order therefore to insure the retention of the guide arms in the inoperative position, the said guide arms are provided with apertures K into which the U-clamp J may be disposed for the purpose of holding said side arms immovable during the changing of the drill steel F, thus serving the dual function of holding the side arms out of the inoperative position and also of providing a definite place in which the U-clamp J may be disposed while such changes are taking place to assure against the possibility of mislaying or losing of the U-clamp.

55 In the modification illustrated in Figure 3, 75 grooves L are formed on the inner or adjacent surfaces of the side arms E. These grooves L lie in the same transverse plane as the grooves H which they join at the upper surfaces of the side arms E. The grooves 80 L are preferably of such depth that when the side arms E are rocked rearwardly to the inoperative position illustrated, and wherein said grooves L will occupy substantially the same relative positions with respect to each 85 other as the grooves H in the operative position, the U-clamp J may be readily disposed therein to retain the side arms E out of the guiding position.

90 The following is a brief description of the operation of the device. Normally during the drilling of rock, the side arms E will occupy a position to form a guide for the drill steel F. The guiding or operative position of the side arms E is illustrated in 95 Figures 1 and 2. In this position of the guide arms, the U-clamp J will be disposed in the grooves H and will remain seated in said grooves unaffected by the vibration incident to drilling. Whenever it is desired 100 to change the drill steel, the U-clamp J is removed from the grooves H and the side arms are then rocked about the side bolts D to a position wherein the U-clamp J may be disposed in the apertures K to hold the 105 side arms E rearwardly of the shell. After the drill steel has been inserted in the front head B, the side arms are again rocked to

their guiding position and the U-clamp J is disposed in the grooves H to hold the guide arms in the operative position.

I claim:

5. 1. A guide for drill steels comprising a pair of arms adapted to be pivotally connected to a rock drill shell, said arms having recesses adapted to register for guiding a drill steel, a U-clamp, and indentations in the arms to receive the U-clamp for both securing the arms in the operative and inoperative positions.
10. 2. A guide comprising a pair of arms adapted to be pivotally connected to a rock

drill shell, said arms having recesses in adjacent sides registering in the operative position of the arms to slidably receive and guide a drill steel, a U-clamp, grooves in the free ends of the arms in the sides thereof to receive the U-clamp for holding the arms in position to guide the drill steel, and apertures in the arms intermediate their ends for the reception of the U-clamp to hold the arms in the inoperative position.

In testimony whereof I have signed this specification.

CHARLES C. HANSEN.
